EPPA H. RYON, OF WALTHAM, MASSACHUSETTS, ASSIGNOR OF ONE-HALF
TO ALFRED M. GOODALE, OF SAME PLACE.

YARN OR THREAD WINDING MACHINE.

SPECIFICATION forming part of Letters Patent No. 558,314, dated April 14, 1896.

Application filed May 11, 1895. Serial No. 548,912. (No model.)

To all whom it may concern:

Be it known that I, EPPA H. RYON, of Waltham, county of Middlesex, State of Massachusetts, have invented an Improvement in 5 Yarn or Thread Winding Machines, of which the following description, in connection with the accompanying drawings, is a specification, like letters and figures on the drawings representing like parts.

10 This invention has for its object the production of a machine for winding yarns or glazed threads upon a receiver of preferably conical form and made of any suitable material, the receivers being positively rotated 15 and arranged in adjacent pairs.

A thread-guide delivers a yarn or thread to each receiver of the pair at a point between them, and the said receivers are rotatably mounted in separable bearings, whereby they 20 are mutually separated as the diameter of the wound mass of thread or yarn on each increases, the said wound masses being in rolling contact with each other.

It is very desirable for many reasons to 25 wind yarn or thread into conical masses, and it is well known that in the rotation of a cone the surface speed decreases from the base toward the apex of the cone, and when such a conical surface is being rotated by a cylind-

30 rical surface the yarn or thread laid upon the cone toward its base is subjected to such strain and abrasion as to produce in many classes of yarns and threads "cuts" or weak thin places, which is highly objectionable.

35 This has been overcome in part by interposing between the cone and the driving-roll an intermediate roll made in sections or rings, loose upon a shaft, which is rotated by the driving-roll, the rings slipping more or less

40 upon the shaft, according to their position toward or away from the base of the cone. This construction necessitates the use of sectional rolls, which are expensive, and but one cone can be driven by each roll, while in this

45 invention I have obviated not only the formation of cuts or abrasions, but also the use of section-rolls, by winding the conical masses in pairs, with their surfaces tangent to each other and their axes converging toward the

50 apexes of the cones. Each cone thus serves as a presser-roll for its fellow, laying the

thread or yarn hard and evenly thereupon with a uniform friction and strain from one to the other end of the cone, the two masses of yarn increasing in diameter in the same 55 ratio, and opposite or adjacent portions of the two cones have a constant speed ratio from base to apex. By this method of winding the finest or most delicate yarn or thread can be wound into hard compact masses without the least abrasion, strain, or friction, obviating completely cuts or weak places.

The thread or yarn is delivered to each mass close to its point of contact with the other mass, means being provided for traversing the threads or yarns during the winding.

As the wound masses of thread or yarn increase in diameter they mutually press their supports away from each other, and by a very 70 simple device the counteracting pressure upon them may be regulated to any desired degree.

I have provided a stop-motion, controlled by the slackening or breakage of either yarn or thread, to automatically stop the rotation of the supports or spindles, and means are also provided for stopping the machine when a predetermined length of yarn or thread has 75 been wound.

80 My invention accordingly consists in a machine for winding thread or yarn constructed and arranged as will be hereinafter described, and particularly pointed out in the claims.

Figure 1 in elevation, for the greater part, represents a winding-machine embodying my invention, but one pair of spindles and their coöperating mechanism being shown, the parts above the line x x , Fig. 3, being shown in elevation. Fig. 2 is a view of the parts 90 shown in Fig. 1 at the left of the line x' x' , the driving-pulley being omitted entirely. Fig. 3 is a top or plan view of the machine shown in Figs. 1 and 2, the means for controlling the stoppage of the winding when a 95 given length of yarn or thread has been wound being omitted for the sake of clearness. Fig. 4 is a side elevation of the thread-guide with its support in section and the masses of thread or yarn indicated by dotted lines. Fig. 5 is 100 a side view, with the cover-plate removed, of the measuring and controlling mechan-

ism; and Fig. 6 is a transverse sectional view thereof.

I have herein illustrated the machine as adapted for winding conical masses of yarn or thread, and, referring to Figs. 1, 2, and 3, the front and back frames A A' are connected by parallel cross girths or braces B B', of suitable shape and location to sustain the operative parts of the machine, it being understood that the frame may be of suitable length to support any desired number of pairs of co-operating spindles.

The braces B B' form tracks or guides, upon which are mounted bearings $a a'$ and $b b'$ for spindles s and s' , the under sides of the bearings being grooved to embrace the tracks, as clearly shown in Figs. 1 and 2, to prevent lateral displacement.

Each bearing has, as herein shown, a boss 6 thereon, slotted at its inner side, as at 7, Fig. 1, to form open seats for the journals of the spindles, whereby they can be readily inserted in or removed from the seats, and when conical masses are to be wound the seats in each pair of adjacent bearings are inclined toward each other, as shown best in Fig. 3, so that the spindles s s' when mounted therein will converge.

Hubs c on the braces B B' serve as guides for two vertically-movable slide-rods c' , to which are rigidly secured substantially $\wedge$ -shaped yokes c^2 , the inner faces of the yokes engaging projections, preferably rolls, as 20, on the outer sides of the bearings, each yoke co-operating with the two bearings at the same side of the machine.

A weight w is attached to each slide-rod to normally draw the yoke secured thereto downward against the rolls 20, thereby tending to move the bearings comprising each pair toward each other and resisting their separation proportionally to the weight and the angle formed by the yoke-arms.

To lift the slide-rods c' and their yokes 45 quickly and in unison, the said rods are connected by cords c^x or other suitable flexible connections to a treadle T, pivoted to the frame at T', the connections passing over sheaves c^3 , secured to the braces, whereby 50 depression of the outer end of the treadle will raise the slide-rods and lift the yokes c^2 from the bearings.

From an inspection of Fig. 1 of the drawings it will be obvious that separation of the bearings of each pair will, through the projections or rolls 20, acting on the inner sides of the yokes c^2 , raise the latter gradually, while a constant tension is maintained upon the bearings, and by increasing or decreasing 60 the weight w the resistance to such separation of the bearings can be regulated with great nicety.

Receivers rr' , shown herein as tapering or conical in shape, are slipped upon the spindles s s' to rotate therewith, and upon these receivers the thread or yarn is wound, and at the beginning of the winding operation the

receivers will be substantially tangent to each other to receive the threads or yarns t t' , and as the latter are wound upon the two receivers the gradually-increasing masses of yarn will, acting upon each other, press the supporting-spindles away from each other, the bearings sliding on the tracks or braces B B'. 70

To deliver the threads or yarns to the receivers close to their peripheries and as near as possible to the line of contact of the two masses of yarn or thread C C', the yarns are led through suitable drop-wires d d' , up over the preferably grooved sheave D, (see Figs. 80 1 and 2,) supported on a suitable overhanging arm A³ of the frame, and thence down through guide-eyes e e' of a traveler e^x , (shown separately in side elevation in Fig. 4,) the traveler being provided with a delivery-nose 85 e^2 , provided with a guide-eye e^3 , through which the yarns or threads t t' are passed in opposite directions to be laid upon the masses of yarn or thread C C'. 90

The under side of the upper portion of the traveler is convexed at e^4 to rest in a longitudinal trough or groove f' in the top of a transverse support f , mounted upon the upturned ends g of standards, provided with hubs g' to embrace and slide upon the slide-rods c' , the standards being provided with preferably adjustable collars g^2 , upon which the support f rests. 95

The traveler e^x is moved back and forth on its support f by suitable mechanism, to be 100 described, to traverse the yarn from one to the other end of the receiver, and it will be obvious that as the diameter of the wound masses increases the delivery-nose e^2 of the traveler must be slightly raised in order to 105 clear the yarn, and for this purpose I have secured, preferably to the hubs g' of the standards, laterally-extended yokes g^3 , the arms of which make an obtuse angle with each other, and which rest upon the projections or rolls 20 on the separable bearings. 110 As the said bearings are separated for the increase in diameter of the yarn masses the rolls 20, acting upon the yokes g^3 , will tend to raise them slowly to thus lift the standards g , and thereby the traveler e^x , to maintain the guide-eye e^3 at the proper point between the yarn masses, the latter thus controlling, automatically, the position of the traveler relative to their line of contact. 115

The traveler is slotted at its upper end at e^5 (see dotted lines, Fig. 4) to receive therein the reduced end of an arm e^6 , longitudinally movable on and supported by a bar e^7 , secured to the braces B B', and retained on said bar 125 by a suitable cap-plate e^8 , said arm below the bar e^7 being provided with a pivoted foot e^9 , which enters a crossing groove E' in a suitable cam-roll E, mounted on a shaft E², rotatable in suitable bearings B⁸ B⁹ on the framework. Loosely mounted upon said shaft is a belt-pulley H, driven by a belt E³ on a pulley E⁴ on the main driving-shaft E⁵. (See Fig. 1.) 130

As the cam-roll E is rotated the crossing groove E' therein will move the arm e⁶ back and forth on its support to in turn actuate the traveler e^x and traverse the yarn, and to 5 avoid shock and to assist the traverse mechanism in changing its movement from one to the other direction spring-buffers 50 (see Figs. 2 and 3) are located at the ends of the groove f'.

10 The belt-pulley H is mounted loosely on the shaft E², and its hub h forms one member of a clutch, the other member h' being longitudinally movable on but rotatable with the shaft E², so that by movement of the 15 member h' into operative or inoperative position the shaft and cam-roll E will be rotated or remain stationary, as desired.

Fast on the shaft E² and beyond the pulley H is secured a preferably grooved pulley or 20 sheave S^x, about which is passed an endless band or cord s^x, which is also passed over grooved sheaves S and S' on the inner ends of spindles s and s', respectively, the manner in which the band is passed over and about 25 the sheave being clearly shown in Fig. 1, the band passing from the sheave S^x to S', then down in a loop or bight up over the sheave S from the outer side, then back to the sheave S^x, and in order to maintain the band taut 30 at all times and yet to allow separation of the sheaves S S' an idler-sheave S² is mounted upon the band at its loop or bight and has attached thereto a suitable weight W, which 35 and also aids in holding the inner ends of the spindles toward each other.

By connecting the sheave S^x with the shaft E² the traverse mechanism and the rotating device for the spindles, just described, will 40 always operate or cease to operate in unison.

It is of course necessary to provide means for automatically stopping the apparatus upon breakage or undue slackening of the yarns, and for this purpose I have provided 45 devices controlled by such slackening or breakage to render the clutch mechanism h h' inoperative upon such a change in the condition of the yarn, one or both.

The drop-wires d d' are preferably enlarged 50 or weighted, as at 30, and pass through holes in a guide-plate d², and below the drop-wires and in their paths when not upheld properly by the yarn I have extended a plate or shelf d³, mounted on an arm d⁴, pivoted to the 55 frame at d⁵, and notched or shouldered at d⁶ to normally engage the toe of an arm d⁷, fast on a rock-shaft d⁸, supported in suitable bearings 15, and extending beneath one of the braces, as B, the front end of the rock-shaft 60 having fast thereon a second arm d⁹, forked at its lower end to engage and operate the member h' of the clutch in usual manner.

The casting to which the arm d⁴ is secured is provided with an extension d¹⁰, upon which 65 is adjustably mounted a weight w² to normally maintain the notch or shoulder d⁶ lifted

to engage the toe of the arm d⁷, and thus maintain the clutch in operative position.

An arm d¹², secured to the rock-shaft d⁸ and extended at an angle to the arm d⁷, is also 70 provided with a weight w³ to maintain the toe of the arm d⁷ in engagement with the shoulder d⁶, and to correspondingly move the clutch into operation to start the machine I have provided the arm d¹² with a lifter-bar d¹³, (shown 75 best in Figs. 1 and 2,) whereby the operator by raising the latter turns the rock-shaft to cause the rounded under side of the toe of the arm d⁷ to pass over the shoulder d⁶ and to throw the clutch into operative position. 80

It will be obvious if one or the other of the two yarns t t' slackens or breaks that its drop-wire will fall upon the shelf d³, depressing the latter and tipping its arm d⁴ about its pivot d⁵, withdrawing the shoulder d⁶ from 85 the toe of the arm d⁷, and permitting the rock-shaft under the influence of the weight w³ to turn or rock and move the clutch member h' out of engagement with the member h, thus automatically stopping the traverse mechanism 90 and the rotation of the spindles, and then the operator can remedy the trouble and by raising the lifter-bar d¹³ will throw the clutch into operative position to start the machine.

While not absolutely necessary it is desirable 95 to automatically stop the winding after a predetermined length of yarn or thread has been wound upon the receivers, and I have herein shown one form of mechanism for controlling the machine according to the length 100 of the yarn wound.

The sheave D, mounted at the upper part of the machine, is rotated by the yarns or threads as they pass from the drop-wires to the traveler, and to one end of the shaft k of 105 said sheave I have secured a disk k', having thereon a wrist-pin k² to engage at each revolution of the sheave a pawl-carrier k³, longitudinally movable in a bearing m, formed in the case M of a suitable counting mechanism. 110 A pawl k⁴ is pivoted to the pawl-carrier k³ within the casing and controlled by a suitable spring k⁵, which also keeps the carrier in the path of the wrist-pin k², the pawl engaging the teeth of a series of ratchet-wheels 115 m' m² m³, loosely mounted side by side on a shaft m⁴ in the casing M.

The ratchet wheels or disks are provided with a different number of teeth, the number of teeth in the ratchet m² being one less than 120 those of the disk m', and the disk m³ has one less tooth than has the disk m², and as the pawl k⁴ engages the teeth of the three disks simultaneously it will rotate the disks through different arcs at each reciprocation of the pawl-carrier, so that the disks m² and m³ will gain continuously on the disk m'. If, for instance, the diameter of the sheave D is six inches 125 and the disks m' m² m³ have, respectively, thirty-nine, thirty-eight, and thirty-seven 130 teeth, it will take about fifty-four thousand eight hundred and thirty-four revolutions of

the sheave D to bring the three ratchets in the same relative position as they were upon starting. I make use of this by slotting all three of the disks radially, so that when the 5 slots are in alinement, as in Figs. 5 and 6, a plate n on the end of a shank n', extended from the top of the casing M, may drop into them. The shank n' has attached to its outer end an arm n², (see Figs. 1 and 2,) to which is 10 secured a depending rod n³, the lower end of which is slightly above the shelf d³ when the shank n' is raised into the position shown in Figs. 1 and 2 and in dotted-line position, Fig. 5, such position being maintained while the 15 masses of yarn are being wound.

When the desired number of yards of yarn has been wound, the slots in the three disks will be again brought into alinement and the plate n can drop into full-line position, Figs. 20 5 and 6, into the slots, thus depressing the rod n³ and causing its lower end to act upon the shelf d³ to release the stop-motion mechanism to stop the machine automatically.

In order to obviate resting the plate n on 25 the toothed peripheries of the disk during the winding, I have cut away the lower edge of the plate to leave projections n^x, which normally enter between the disks m' m² and m² m³ and rest upon annular shoulders formed 30 thereon, (clearly shown in Fig. 6,) so that the plate n will not be vibrating all the time that the ratchet-disks are being moved forward step by step.

With the dimensions hereinbefore given 35 about twenty-eight thousand yards of yarn or thread may be wound upon each receiver.

It will be obvious that other registering mechanism may be used in this connection to 40 actuate the stop-motion after a predetermined length of yarn has been wound, and my invention is not limited to the particular registering and controlling mechanism shown herein.

From the foregoing description and the 45 drawings it will be evident that each mass of yarn of the pair will act upon its fellow as a presser-roll to wind the yarn or thread in a hard compact mass thereon, the two wound masses increasing in size in unison, and as the surface speed of adjacent parts of the two 50 masses is equal there can be no abrasion or strain upon the yarn or thread at any time, thus obviating absolutely the formation of any cuts or weak places.

By my invention I am enabled to wind 55 conical masses of yarn or thread with much greater uniformity and density and in larger masses than has heretofore been possible.

It will be obvious that by mounting the 60 spindles in parallelism and using cylindrical receivers the yarn may be wound in cylindrical masses, the mutual action of the wound masses of each pair being precisely the same.

My invention is not restricted to the precise construction and arrangement of parts herein shown, as it will be obvious that the 65 same may be modified or rearranged without

departing from the spirit and scope of my invention.

I claim—

1. In a machine for winding yarn or thread, a plurality of separable receivers, means to positively rotate them, and a thread-guide to deliver a yarn or thread to each receiver, one receiver and the yarn wound thereupon acting as a presser for the yarn laid upon the other receiver, substantially as described. 70

2. In a machine for winding yarn or thread, a plurality of separable receivers, means to positively rotate them, a thread-guide to deliver a yarn or thread to each receiver at a point between them, and traverse mechanism to reciprocate the said guide, one receiver and the yarn wound thereupon acting as a presser for the yarn laid upon the other receiver, substantially as described. 80

3. In a machine for winding yarn or thread, a plurality of separable and adjacent receivers, means to positively rotate them, a common thread-guide to deliver a yarn or thread to each receiver at a point between them, traverse mechanism to reciprocate the said guide, and means controlled by the diameter of the wound masses of yarn or thread and the distance between the longitudinal axes of 90 the receivers to raise the guide between them, substantially as described.

4. In a machine for winding yarn or thread, a plurality of separable receivers, means to positively rotate them, a thread-guide to deliver a yarn or thread to each receiver, one receiver and the yarn wound thereupon acting as a presser for the yarn laid upon the other receiver, and a stop-motion controlled by slackening or breakage of a thread or yarn, 100 to automatically stop the rotation of the receiver, substantially as described. 100

5. In a machine for winding yarn or thread, a plurality of separable receivers, means to positively rotate them, a device to press the 110 receivers toward each other, with a constant pressure, a thread-guide to deliver a yarn or thread to each receiver at a point between them, traverse mechanism for said guide, and means controlled by the diameter of the 115 wound masses of yarn, to automatically maintain the guide adjacent to the line of contact of said masses, substantially as described.

6. In a machine for winding yarn or thread, two separable spindles, sheaves thereon, a 120 driving-sheave, a continuous flexible connection between said sheaves, to positively rotate the spindles, and a slack-controller for said connection, combined with a thread-guide, and traverse mechanism therefor, to lay a 125 yarn or thread simultaneously upon each spindle, substantially as described.

7. In a machine for winding yarn or thread, a plurality of separable receivers, means to positively rotate them, a thread-guide to deliver a yarn or thread to each receiver, a stop-motion to stop the apparatus upon the breakage of the yarn or thread, mechanism to measure the yarn or thread delivered, and connec- 130

tions between it and the stop-motion, to actuate the latter automatically when a predetermined length of yarn or thread has been wound to stop the apparatus, substantially as described.

8. A plurality of conical receivers converging toward their apexes and pressed toward each other, means to positively and separately rotate them, and a thread-guide to deliver a yarn or thread to each receiver at a point between them adjacent the line of contact of the receivers or the yarn or thread wound thereupon, substantially as described.

9. A plurality of conical receivers converging toward their apexes, means to positively rotate them, bearings for the receivers, the adjacent bearings being separable from each other, a thread-guide to deliver a yarn or thread to each receiver, and means to press the receivers toward each other, the masses of yarn being thereby held in continuous contact and by their increase in diameter separating the receivers, substantially as described.

10. In a machine for winding yarn or thread, a plurality of separable receivers, means to positively rotate them, a thread-guide to deliver a yarn or thread to each receiver, one receiver and the yarn wound thereupon acting as a presser for the yarn laid upon the other receiver, a stop-motion controlled by slackening or breakage of a yarn or thread, to automatically stop the rotation of the receivers, and an independent measuring device to actuate the stop-motion when a predetermined amount of yarn or thread has been wound, substantially as described.

11. In a machine for winding yarn or thread, a plurality of separable conical receivers converging toward their apexes, movable bearings therefor, means to positively rotate the receivers, vertically-movable yokes having outwardly-inclined arms to rest upon the bearings and normally press them toward each other, a thread-guide to deliver a yarn or

thread to each receiver, traverse mechanism therefor, and a support for the thread-guide controlled as to its vertical height by the separation of the bearings, substantially as described.

12. In a machine for winding yarn or thread, a receiver, a presser, means to positively and separately rotate them at the same surface speed throughout the winding, to thereby obviate abrasion of the yarn or thread, and a guide to deliver a yarn or thread to the receiver, substantially as described.

13. In a machine for winding yarn or thread, a plurality of contacting receivers, means to rotate them at uniform speed and in opposite directions, a thread-guide to simultaneously deliver a yarn or thread to each receiver, and devices to maintain the uniformly-increasing masses of yarn or thread in tangential contact under pressure throughout the winding, whereby each receiver acts as a rotating presser for the yarn laid upon the other receiver, to obviate abrasion of or slackening of the yarn or thread, substantially as described.

14. In a machine for winding yarn or thread, a receiver, and means to positively rotate the same, a thread-guide to deliver a yarn or thread to the said receiver, a rotating presser for the yarn laid upon said receiver, means to hold the said presser normally in operative position against the receiver, a treadle, and connections intermediate the same and presser whereby movement of the treadle permits separation of the presser and receiver, substantially as described.

In testimony whereof I have signed my name to this specification in the presence of two subscribing witnesses.

EPPA H. RYON.
